UNITED STATES PATENT OFFICE

129,690

DESIGN FOR A DRIP COLLECTOR FOR MARINE CARBURETORS OR THE LIKE

Frederick Kraissl, Jr., Hackensack, N. J.

Application January 17, 1941, Serial No. 98,152

Term of patent 3½ years

To all whom it may concern:

Be it known that I, Frederick Kraissl, Jr., a citizen of the United States and resident of Hackensack, in the county of Bergen and State of New Jersey, have invented a new, original and ornamental Design for Drip Collectors for Marine Carburetors or the like, of which the following is a specification, reference being had to the accompanying drawing forming part thereof, in which

Figure 1 is a top plan view of a drip collector

for marine carburetors or the like embodying my new design;

Figure 2 is a side elevational view thereof; and

Figure 3 is an end view of the device as seen from the right end of Figures 1 and 2.

I claim:

The ornamental design for a drip collector for marine carburetors or the like, substantially as shown.

FREDERICK KRAISSL, JR.
